US00D805632S

(12) **United States Design Patent** (10) **Patent No.:** **US D805,632 S**
Costello et al. (45) **Date of Patent:** **** Dec. 19, 2017**

(54) **INJECTOR DEVICE**(71) Applicant: **West Pharmaceutical Services, Inc.**, Exton, PA (US)(72) Inventors: **Brian Costello**, Whitehouse Station, NJ (US); **Raymond Protasiewicz**, Whippany, NJ (US)(73) Assignee: **West Pharmaceutical Services, Inc.**, Exton, PA (US)(***) Term: **15 Years**(21) Appl. No.: **29/582,294**(22) Filed: **Oct. 26, 2016**(51) **LOC (10) Cl.** ..... **24-02**(52) **U.S. Cl.**USPC ..... **D24/113**(58) **Field of Classification Search**

USPC D24/112-114, 133, 186, 104, 130, 127, D24/176, 108, 110, 220; 606/181, 185; 604/232, 187, 158, 164.08, 192, 263, 163, 604/181, 184, 198, 227, 168.01, 275, 604/890.1; D9/414, 424, 417, 426

CPC A61M 2005/14252; A61M 2005/1581; A61M 5/14248; A61M 2005/14513; A61M 2005/206

(57) **CLAIM**

The design of an injector device, as shown and described.

DESCRIPTION

FIG. 1 is a top, front, right perspective view of an injector device showing our new design;

FIG. 2 is a front elevation view thereof;

FIG. 3 is a rear plan elevation view thereof;

FIG. 4 is a top plan view thereof;

FIG. 5 is a bottom plan view thereof;

FIG. 6 is a left side elevation view thereof; and,

FIG. 7 is a right side elevation view thereof.
